UNITED STATES PATENT OFFICE.

KENNETH BANCROFT ABERNATHY, OF DANVILLE, ILLINOIS.

SMOKING-PIPE.

1,335,312.

Specification of Letters Patent. Patented Mar. 30, 1920.

Application filed December 26, 1918. Serial No. 268,340.

To all whom it may concern:

Be it known that I, KENNETH BANCROFT ABERNATHY, a citizen of the United States, and a resident of Danville, in the county of Vermilion and State of Illinois, have invented a new and Improved Smoking-Pipe, of which the following is a description.

The general object of my invention is to provide a smoking pipe improved in various particulars with a view to produce a more nearly perfect combustion to thereby consume the poisonous matter in the tobacco; and to provide a construction and arrangement of parts designed to prevent the formation of deleterious and objectionable deposits which in the ordinary pipe are formed in the bowl and stem and drawn into the mouth of the smoker; as well as to provide a construction whereby a thorough cleaning of the pipe is facilitated.

The above and other objects are attained by the novel features and combination of parts hereinafter particularly described and claimed.

Reference is to be had to the accompanying drawings forming a part of this specification, it being understood that the drawings are merely illustrative of one example of the invention.

Figure 1 is a longitudianl vertical section of a smoking pipe embodying my invention;

Fig. 2 is a plan view thereof with the mouthpiece partly in section;

Fig. 3 is a fragmentary plan view with the upper movable part of the main bowl in the raised position and part of the removable and auxiliary bowl broken away;

Fig. 4 is an enlarged front view of portions of the fixed and movable main bowl sections and showing the latch means for the movable bowl section.

Fig. 5 is a longitudinal vertical section of the front portion of the pipe illustrating a modification.

In carrying out my invention in accordance with the example Figs. 1 to 4, the main bowl includes a bottom, relatively fixed, section 10 having a stem section 11 thereon and an upper bowl section 12 hinged as at 13 adjacent to the stem section to swing into position on the fixed section 10 or swing to a raised position as indicated in dotted lines, Fig. 1 and shown in full lines in Fig. 3. The movable main bowl section 12 is secured by a suitable latch means, there being shown a latch bolt 14 swingably secured at

its lower end 15 to a hinge plate 16 on the lower bowl section 10, said bolt being adapted to enter the slotted flange 18 on a catch plate 17, secured to the bowl section 12, the upper threaded end of said latch bolt being adapted to receive a cap nut 19 preferably having a slot 19a to receive a screw driver or like tool for tightening the nut.

The main bowl composed of sections 10 and 12 with the fixed stem section 11 is in practice formed of metal and within the lower bowl section 10 I provide an auxiliary removable bowl 20 of porcelain, clay, or other suitable material to constitute when in place a lining for the metal bowl section 10. The bowl 20 has a smoke passage 21 at its forward side produced by the main wall of the bowl and by a transverse partition 22 curving rearwardly so that the smoke passage 21 curves toward the rear of the bowl and terminates adjacent to the bottom thereof. In the auxiliary bowl 20 and rearward of the partition 22 is a horizontal screen 23 of copper or like metal which is removably secured in place by suitable means such as a split ring 24 to facilitate the thorough cleaning of the auxiliary bowl and the screen, and to permit of readily renewing the screen should it become necessary. A smoke passage 25 leads rearwardly from the auxiliary bowl 20 above the screen 23 in register with the smoke passage 26 in the main bowl section 10 and leading to the stem 11. With the described arrangement smoke drawn downwardly from the upper main bowl section 12 into the passage 21 will be permitted to expand rearward of the partition 22 and in being drawn to the stem will be disseminated over the surface of the screen 23. Nicotin or the like will tend to collect in the bottom of the auxiliary bowl 20 and the smoke will be further relieved of nicotin by deposit of the latter on the screen 23.

The auxiliary bowl 20 is covered by a plate 27 which has perforations 28 in register with the smoke passage 21. Said plate 27 is held in position on top of the auxiliary bowl 20 by the movable main bowl section 12 which is provided with a suitable member or members to overlie the said plate, there being indicated a flange 29 presenting a shoulder on said bowl section 12 overlying the edge portion of said plate. Thus, the auxiliary bowl and its cover plate are held in place by the bowl section 12.

The stem 11 has an enlarged bore 30 in

which saliva may collect and be prevented from reaching the bowl through the passage 26. A clean-out plug 31 is provided in the stem section 11 adjacent to the forward 5 end of the bore 30. A suitable removable stem section 32 engages in any suitable manner with the outer end of the stem section 11, there being shown a reduced end or tenon 32^a on said stem section 32 fitting 10 within the rear end of the stem section 11. The mouthpiece has a plurality of smoke outlets 33 designed to have a cooling effect on the smoke to a greater extent than a single passage. Disposed longitudinally within 15 in the stem sections 11 and 32 is a tube 34 which may be formed of glass or other suitable material, said tube is secured at its forward end in any suitable manner as at 20 35 in the bowl section 10 at the junction of the stem section 11, the said tube in the illustrated example being threaded to engage the bowl 10. At the outer end the tube 34 is centered by projections 36 on the interior of the removable stem 32.

25 Provision of the smoke passage 21 adjacent to the front wall of the bowl instead of drawing the smoke directly into the stem, tends to produce a cool and pleasing smoke, particularly in connection with the enlarged 30 chamber provided in the bottom of the bowl and to which said smoke passage leads. Also, the screen 23 in addition to causing a deposit of the nicotin and other matter takes up and radiates much of the heat in the 35 smoke.

The stem section or mouthpiece 32 forms a continuation of the saliva chamber 30 and the tube 34 terminates short of the outer end of the mouthpiece and thereby not only 40 is the saliva prevented from entering the tube 34 but any nicotin that may fail to collect in the bowl 20 or on the screen 23, will pass from the tube 34 into the exterior saliva chamber of the stem and be prevented from 45 reaching the mouth of the smoker. A thorough cleaning of the pipe is possible since by swinging the upper main bowl section 12 to the raised position, the plate 27 and the auxiliary bowl 20 with its screen 23 may readily be removed for separate cleaning. Similarly, the stem 32 and tube 34 may be removed and properly cleaned with facility, and the removal of the clean-out plug 31 permits of the chamber 30 being thoroughly 55 cleaned.

The main bowl is preferably divided on an oblique line as shown instead of parallel with the top of the bowl, and the auxiliary bowl 20 similarly has a sloping top, the 60 arrangement serving to permit of the ready removal of the auxiliary bowl and the plate 27 without cutting away any of the incrusted matter in the upper part of the bowl.

In the example illustrated in Fig. 5, the 65 main bowl 10^a has an open bottom in which

the auxiliary bowl 20 is inserted and corresponds in all respects with the form shown in Figs. 1 to 3 including its cover plate 27 with the smoke outlets 28 as well as the smoke passage 21 and screen 23 and ring 24. 70 Also, the auxiliary bowl has a smoke outlet 25 to register with the smoke passage 26^a in the bowl 10^a at the juncture of the stem 11^a. The auxiliary bowl may be held in the main bowl 10^a in any suitable manner as by having a tight fit therein so that it will securely retain its position while being removable when desired. The main bowl 10^a may have the flange 29^a or other projection or projections to present a shoulder against 80 which the top of the auxiliary bowl engages. 75

I would state in conclusion that while the illustrated examples constitute practical embodiments of my invention, I do not limit myself strictly to the mechanical details 85 herein illustrated, since manifestly the same can be considerably varied without departure from the spirit of the invention as defined in the appended claims.

Having thus described my invention, I 90 claim as new, and desire to secure by Letters Patent:

1. A smoking pipe including a main bowl comprising a bottom section having a stem section thereon and an upper bowl section 95 movable relatively to said bottom section; an auxiliary bowl removably fitting within said bottom bowl section to constitute a removable lining therefor and terminating at the juncture of the bottom and upper 100 main bowl sections, a plate at the juncture of the bottom and upper bowl sections and constituting a cover for said auxiliary bowl, and means on the said upper main bowl section at the interior and adjacent to the bottom of said bowl section, to engage said plate and hold the latter and the auxiliary bowl in place, said plate having a smoke outlet to the auxiliary bowl and the latter having a smoke outlet to said stem section. 105

2. A smoking pipe including a main bowl comprising a bottom section having a stem section thereon and an upper relatively movable bowl section; a removable auxiliary bowl in said bottom section, means 115 in said auxiliary bowl forming a smoke passage therein adjacent to the front wall thereof, said smoke passage terminating adjacent to the bottom of the auxiliary bowl, and the latter presenting an enlarged chamber above and rearward of the bottom of said smoke passage said chamber having a smoke outlet in communication with said stem section, and means forming a cover for said chamber and having a smoke outlet leading to said smoke 120 passage of the auxiliary bowl.

3. A smoking pipe including a main bowl comprising a bottom section having a stem section thereon and an upper relatively movable bowl section; a removable auxiliary 125

bowl in said bottom section, means in said auxiliary bowl forming a smoke passage therein adjacent to the front wall thereof, said smoke passage terminating adjacent to 5 the bottom of the auxiliary bowl, and the latter presenting an enlarged chamber above and rearward of the bottom of said smoke passage, said chamber having a smoke outlet in communication with said stem section, 10 and a screen extending across said chamber of the auxiliary bowl below the outlet to the stem.

4. A smoking pipe including a main bowl, a stem section thereon, an auxiliary bowl 15 in the bottom portion of said main bowl and having a downwardly extending smoke passage adjacent to the front wall of the auxiliary bowl and terminating at the bottom of the latter, there being a smoke outlet from 20 said auxiliary bowl to said stem section, and a screen extending across a part of the auxiliary bowl, so that the smoke will pass therethrough before entering the said smoke outlet.

25 5. A smoking pipe including a main bowl, an auxiliary bowl removably held in

the main bowl at the bottom, said auxiliary bowl having a smoke passage leading from the top thereof adjacent to the front wall downwardly and presenting a chamber in 30 the rear of said smoke passage, and a screen extending across said chamber of the auxiliary bowl above the outlet of said smoke passage, said auxiliary bowl having a smoke outlet above said screen.

6. A smoking pipe including a main bowl, an auxiliary bowl removably held in the main bowl at the bottom, said auxiliary bowl having a smoke passage leading from the top thereof adjacent to the front wall 40 downwardly and presenting a chamber in the rear of said smoke passage, and a screen extending across said chamber of the auxiliary bowl above the outlet of said smoke passage, said auxiliary bowl having a smoke 45 outlet above said screen; together with a separate cover for said auxiliary bowl, and means on the main bowl at the interior projecting over the said cover and auxiliary bowl.

KENNETH BANCROFT ABERNATHY.
